UNITED STATES PATENT OFFICE.

JOHN GASKELL, OF PORT SUNLIGHT, ENGLAND.

INSETTING ATTACHMENT FOR PRINTING-PRESSES.

SPECIFICATION forming part of Letters Patent No. 655,399, dated August 7, 1900.

Application filed December 20, 1899. Serial No. 741,023. (No model.)

To all whom it may concern:

Be it known that I, JOHN GASKELL, a subject of the Queen of Great Britain, residing at Port Sunlight, in the county of Chester, England, 5 have invented certain new and useful Improvements in Insetting Attachments for Printing-PresSES; and I do hereby declare the following to be a full, clear, and exact description of the invention, such as will enable others skilled in the art to which it appertains to make and use the same.

This invention has for its object improvements in mechanism for duplicating the delivery of printed matter from printing or 15 other machines in which the delivery of paper or substitutes thereof can be accelerated; and it consists in providing means whereby printed matter can, even in double-folded form, the one part inset within the other, be 20 effectually accomplished in and by the means hereinafter fully set forth. It has heretofore been customary in the delivery of such folded printed matter to deliver the same in single 25 form by fliers operating throughout an angle of ninety degrees, but according to this invention the travel of the fliers is throughout an arc of one hundred and eighty degrees and at half the speed of the former. However, I 30 will now proceed to describe my said invention with reference to the accompanying drawings, which form part of this specification.

Figure 1 is an end elevation. Fig. 2 is a plan. Fig. 3 is a side elevation, partly in section, taken on line 3 3, Fig. 2, looking in the 35 direction of the arrow and showing the bevel-gear of one hopper in full lines and the hopper in rear of the gear and in vertical transverse section.

Reference being had to the drawings and 40 the letters thereon, A A' are the receiving hoppers, into which the folded printed matter is delivered at a central point into a fixed inclined receptacle C C of a V shape formed at that point in the sides of the semicircular 45 hopper A A'. The bed of the said hopper A is provided with concentric openings c c throughout an arc of one hundred and eighty degrees, as shown. Through these slots or 50 openings c c fingers d protrude, said fingers d being formed on or attached to fliers B B', mounted on a vertical axis. This axis is provided with a pinion r, to which motion is im-

parted by the reciprocal movements of a rack q. The folded printed matter on being delivered into the said V-grooves will spring 55 open to the angle of the grooves of the receptacle C C in the hopper A or thereabout and will remain so until a second folded printed sheet is delivered from the same machine and within the open folds of the first folded and 60 printed sheet. At this point the oscillating fliers B sweep the two out of range while another pair are being delivered into the angular receptacle, whereupon the return of the fliers takes the next pair of folded sheets along 65 to the other trough, and so on with every delivery of the machine.

The speed of the shaft s operating the fliers B B as now in ordinary use is hereby reduced one-half in order to allow the fliers to make 70 one oscillation in the time now taken by an ordinary machine to make two, while by so doing it allows the first folded sheet of printed matter to remain at rest, supported in the V-grooves herein described, during one-half 75 the period taken by the fliers B B to make one oscillation. This is attained by means of gear-wheels in a corresponding ratio and advantageously in the following manner:

D indicates a frame supporting a counter-shaft f, on one end of which is an eccentric g, having a rod h, which connects with the lever i, attached to the rock-shaft k, which is provided with a miter gear-wheel l, meshing with a like gear-wheel m on shaft n, and to which 85 shaft is attached a lever o, connected to a bar p, having gear-teeth q, which engage with a sector-shaped gear-wheel r on shaft s, to which the flier B is secured. On the opposite end of the counter-shaft f is a crank-disk t, having a wrist-pin u, to which is attached a rod v, which connects with a lever w, attached to the rock-shaft y, which is provided with a miter gear-wheel z, meshing with a like gear-wheel a' on shaft b', and to which shaft is attached a lever c', connected to a bar d', having gear-teeth e', which engage with a sector-shaped gear-wheel f' on shaft g', to which the flier B' is secured. On one end of the counter-shaft f is a master gear-wheel h', which 95 meshes with a pinion i', secured to a shaft E. The counter-shaft f works in suitable bearings f', supported by a bracket D, bolted down in a convenient manner at the delivery 100

end of the printing or folding machine, or both, as the case may be.

Motion is given to the rocking shaft *k* by means of an eccentric *g* and crank *i* through 5 the levers *h* and *i*, which in turn give motion through the miter-wheels *l* and *m* to the vertical shafts *n n*, and thence by the reciprocal movement of the rack *p* and pinion *r* to the fliers *B B* aforesaid.

10 In the foregoing examples the delivery of the printed and inset matter has been effected by a radial action for convenience in having the delivery ends of the hopper side by side; but I would have it understood that I do not 15 confine myself to such radial action, as it may be effected by a reciprocating set of fliers in a straight path to feed each end thereof. The plane of the base of said straight hopper need not necessarily be horizontal, but may be ad- 20 vantageously inclined, so as to retard their movement along the hopper somewhat, and thereby cause a greater number of bundles to accumulate in a given space than would be the case were it open or horizontal. It 25 will be obvious that these oscillatory or reciprocal movements can be effected by various forms of mechanism as modifications of the means herein shown and described and to which I would have it understood that I do 30 not confine myself; but

What I claim as my invention, and desire to secure by Letters Patent, is—

1. An insetting attachment for printing- 35 presses, consisting of a hopper having a fixed transverse receptacle constructed to receive a folded sheet of paper and allow it to open and receive an insert leaf; in combination with a flier for removing the paper from said receptacle and from the hopper.

40 2. An insetting attachment for printing- presses, consisting of a hopper having a fixed transverse paper-receptacle provided with inclined walls to receive a folded sheet of paper

and allow it to open and receive an inset leaf; in combination with a flier for removing the 45 paper from said receptacle and from the hopper.

3. An insetting attachment for printing- presses, consisting of a hopper having a fixed transverse paper-receptacle to receive a folded 50 sheet of paper and allow it to open and receive an inset leaf, and a slotted bottom; in combination with a flier having fingers projecting through the slots in the bottom for removing the paper from said receptacle and 55 from the hopper.

4. An insetting attachment for printing- presses, consisting of a hopper approximately semicircular in form and having concentric slots in its bottom, and a paper-receptacle 60 crossing the hopper; in combination with a flier having fingers projecting through said slots, and means for imparting vibratory motion to the flier for removing the paper.

5. An insetting attachment for printing- presses, consisting of a hopper having a trans- 65 verse paper-receptacle; in combination with a flier, a rack and pinion for operating the flier, and means for reciprocating the rack to impart vibratory motion to the flier. 70

6. An insetting attachment for printing- presses, consisting of a hopper, a paper-re- 75 ceptacle; and a flier; in combination with a rack and pinion, and suitable gearing and connections for lessening the speed of the flier one-half of that of its main driving- shaft, to permit the flier to travel through an arc of one hundred and eighty degrees and thereby effect a delivery on both its forward and return movement. 80

In testimony whereof I affix my signature in presence of two witnesses.

JOHN GASKELL.
